UNITED STATES PATENT OFFICE.

MOSES F. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,300,583.

Specification of Letters Patent. Patented Apr. 15, 1919.

Application filed August 23, 1917. Serial No. 187,804.

To all whom it may concern:

Be it known that I, MOSES F. CARR, a citizen of the United States, and a resident of Newton, in county of Middlesex, Commonwealth of Massachusetts, (whose post office address is care of Carr Fastener Company, Cambridge, Massachusetts,) have invented an Improvement in Fasteners, of which the following description, in connection with the accompanying drawings, is a specification, like characters on the drawings representing like parts.

This invention pertains to improvements in fasteners, and more particularly, though not exclusively, to snap fasteners primarily intended to hold on securely the flaps of pockets containing clips of cartridges, readily permitting separation of the two parts of the fastener so that the flap can be raised and the clip of cartridges removed from the pocket, while reducing to a minimum the chances of accidental separation of the fastener and resultant loss of ammunition.

In snap fasteners as ordinarily constructed, if the flap of the pocket were raised accidentally in climbing out of a trench or by catching on the bough of a tree or the like, the socket portion of the fastener would be separated from the stud portion thereof. The use of those types of separable fasteners requiring any considerable manipulation for separation of the parts is disadvantageous because valuable time may be lost on account of failure to immediately perform the correct manipulation. In the present invention the amount of manipulation necessary to open the device is reduced to a minimum.

In the drawings:

Figure 1 is an elevation of a preferred form of one embodiment of my invention;

Fig. 2 is a section on the line 2—2 of Fig. 1;

Fig. 3 is a section on the line 3—3 of Fig. 2.

Referring to the drawings, 4 represents the side of a coat, 5 the outside of a pocket and 6 the flap of the pocket. The stud 7 is attached to the outside of the pocket 5 by any suitable means and provides a round head 8 and a neck portion 9 providing shoulders, preferably abrupt, between the neck 9 and the head 8. The socket is attached to the flap 6 of the pocket and preferably comprises a front plate 10, intermediate plate 11 and back plate 12. The front plate 10

is preferably flanged at the edges to provide a recess for a spring 13 which provides jaws 14 and 15 extending transversely of the socket. The jaws 14 and 15 are preferably held apart by a projection 16 interposed between their ends. When the rounded head of the stud 8 is pressed between the jaws 14 and 15, the jaws are spread and engage the neck 9 of the stud. As before stated, the shoulders provided between the neck 9 and head 8 are preferably sufficiently abrupt to prevent separation of the stud and socket by rectilinear movement. Said shoulders are also preferably sufficiently abrupt to prevent separation of the jaws 14 and 15 by tipping movement of the socket relative to the stud in a direction transverse to the jaws. Relative tipping movement of the stud and socket in a direction longitudinal of the jaws 14 and 15 is preferably prevented by the intermediate plate 11 or the back plate 12 or both of said plates.

The aperture through the intermediate and back plates is preferably such as to permit tipping movement of the socket relative to the stud when the bottom of the flap 6 is pulled outwardly. As before stated, however, this alone will not open the fastener because of the engagement between the abrupt shoulder of the stud and the jaw 15. When, however, the flap 6 is pulled downwardly and outwardly in the direction shown by the arrow in Fig. 2, the jaw 14 is pressed upwardly by the stud 7, while the jaw 15 remains abutted against the stop 16 of the socket casing. Therefore the jaws 14 and 15 are separated sufficiently to permit the head 8 of the stud 7 to slip between the jaws 14 and 15, thereby opening the fastener and permitting removal of the contents of the pocket. In practice the stud and socket are so proportioned that a quick jerk in a downward and outward direction will effect this opening. It is obvious that movement in this direction can only be effected in one way, viz., by grasping the bottom of the flap of the pocket in a sufficiently firm manner so as to be able to exert tension thereon in the desired direction.

While I have shown and described one embodiment of my invention, it is obvious that changes involving omission, alteration, substitution and reversal of parts, and even changes in the mode of operation, may be made without departing from the scope of

my invention, which is best defined in the following claims:

Claims:

1. A fastener comprising, in combination, 5 a stud, a socket, jaw means carried by said socket for engagement with said stud, and means coöperating with said jaw means providing for opening thereof on diagonal movement of said socket in a direction transverse to, away from, and in the direction of the longitudinal axis of said stud.
  2. A separable fastener comprising, in combination, a stud, a socket, a plurality of resilient jaws carried by said socket, stop 15 means operatively limiting movement of one of said jaws toward the other, said socket being formed to permit bodily tipping movement of said socket relative to said stud in a direction away from the jaw having limited 20 movement, while preventing substantial tipping movement in all other directions.
  3. A stud and socket fastener comprising in combination, a stud providing a head and a neck with abrupt shoulders interposed between 25 said neck and head, a socket providing two resilient jaws, stop means operatively interposed between the ends of said jaws; said socket permitting bodily transverse movement of said socket relative to said stud to a position where one of said 30 jaws is disengaged from the abrupt portion of said shoulder.
  4. A stud and socket fastener comprising, in combination, a stud having a head and 35 a neck with an abrupt shoulder interposed therebetween, a socket providing two substantially parallel jaws for engagement with opposite sides of said neck and means permitting disengagement of one of said jaws 40 from the abrupt portion of said shoulder, thereby to permit separation of said socket from said stud on continued tipping movement of said socket relative to said stud in a direction transverse to said jaws.
  5. A stud and socket fastener comprising, 45
- in combination, a stud having a head and a neck, an abrupt shoulder interposed between said head and neck, a socket having a casing, a resilient spring inclosed in said casing and providing two resilient jaws, a stop 50 interposed between the ends of said jaws and means permitting limited tipping movement of said socket relative to said stud in a direction transverse to said jaws, thereby to permit separation of said stud from said socket. 55
6. A stud and socket fastener comprising, in combination, a stud 7 having a head 8 and a neck 9, an abrupt shoulder interposed between said head and said neck, a socket comprising a casing 10 having a 60 spring 13 therein providing resilient jaws 14 and 15, and a stop 16 interposed between the ends of said jaws.
7. A stud and socket fastener comprising, in combination, a stud having a head and a 65 neck; a socket therefor having jaw means and means opposing separation of said socket from said stud by rectilinear movement of said socket relative to said stud or by tipping movement alone, while permitting 70 separation of said socket from said stud by combined transverse and outward movement of one side of said socket relative to said stud.
8. A fastener for the flaps of cartridge 75 pockets providing a stud 7 attached to the outer portion of the pocket, a socket attached to the flap 6 of the pocket, jaw means carried by said socket for engagement with a reduced portion of said stud 7 and means 80 opposing separation of said stud from said socket by rectilinear movement of said socket relative to said stud or by relative tipping movement alone, while permitting separation of said socket from said stud by 85 a combined downward and outward pull on the bottom of said flap.

In testimony whereof, I have signed my name to this specification,

MOSES F. CARR.
